UNITED STATES PATENT OFFICE.

YUST PETERSON, OF HELENA, MONTANA.

MANUALLY-PROPELLED BOAT.

1,319,613.

Specification of Letters Patent.

Patented Oct. 21, 1919.

Application filed March 18, 1919. Serial No. 283,391.

To all whom it may concern:

Be it known that I, YUST PETERSON, a citizen of the United States of America, residing at Helena, in the county of Lewis and 5 Clark and State of Montana, have invented new and useful Improvements in Manually-Propelled Boats, of which the following is a specification.

The principal purpose of the invention is 10 to provide a manually propelled boat in which the usual propeller is carried at the stern and connects with suitable operating mechanism within the boat, the said operative connections being mounted or carried 15 in a diagonally disposed tube, whose lower end is sealed to the hull where it connects with the latter and whose upper end stands normally above the water line. All of the operating mechanism is carried within the 20 hull where it is readily accessible and its connections with the propeller are not, because of the peculiar construction, required to pass through a packed joint in order to reach the latter. The necessary force to 25 operate the mechanism is therefore reduced to a minimum. The construction provided shows two seats, each to hold an operator, the one being positioned to the forward of the other and adjacent to that part of the 30 propelling mechanism at which the initial force is received. The operators are therefore in a position where they can conveniently operate the propelling mechanism and the rear one of the two operators is positioned 35 where he can conveniently manipulate the steering mechanism which is in the form of the usual rudder and operable by two foot pedals, either one of which may be depressed to turn the rudder in one direction or the other.

A further purpose of the invention is to provide a boat of the character mentioned which is simple in construction, durable and effective in operation and inexpensive to 45 manufacture.

Other and further purposes appear in the following description wherein the invention is set forth in detail.

To the exact construction in which it is 50 shown and described, the invention is not to be restricted. The right is reserved to make such changes or alterations as the actual reduction to practice may suggest in so far as such changes or alterations are compatible in spirit with the annexed claims. The 55 same numerals of reference designate the

same parts throughout the several figures of the accompanying drawings which form a part of this application and in which:

Figure 1 is a top plan view of the improved boat.

Fig. 2 is a central, longitudinal, sectional view through the structure shown in Fig. 1.

Fig. 3 is a section on the line 3—3 of Fig. 2.

Fig. 4 is a section on the line 4—4 of Fig. 2.

Fig. 5 is a central, longitudinal, sectional view through the tubing housing the propeller shaft.

Referring to the drawings, there is shown a hull 1, which is of the usual construction for small boats. At the stern of the hull there is mounted a diagonally disposed tube 2, whose lower end penetrates the stern at 75 the lower end thereof, being sealed in the stern where it passes through the latter. The upper end of the tube terminates at a point where it will be above the water line when the hull is in the water and loaded 80 to its full capacity. The tube is supported at an intermediate point by a column 3, through which it passes this column on its upper end, receiving a seat 4 on which an operator may rest.

On either side of the tube 2, its forward or upper end, there is mounted a pillar block 5 formed with appropriate bearings for the support of a transverse shaft 6, the latter, of course, being mounted for rotary movement and carrying at its opposite ends the cranks 7 which the operator, resting on the seat 4, may turn with his hands. Just to the forward of the forward end of the tube 2 there is mounted a column 8, and this column is formed in its upper end with an appropriate bearing 9 in which there is journaled a short shaft 10, the latter carrying a bevel gear 11 and a pinion 12. The short shaft 10 is put in motion through the medium of the shaft 6, which carries a spur gear 13, measuring with the pinion 12.

The bevel gear 11 meshes with a bevel gear 14, formed integral with bevel gear 15, and these two latter gears are carried at 105 the forward or upper end of a propeller shaft 16 which is inclosed within the tube 2 and which carries at its lower or rear end and exterior to the hull the propeller 17.

Obviously, the rotation of the shaft 6, 110 through the instrumentality of the cranks 7, will serve to impart rotary motion to the

shaft 16 with the result that the propeller 17 is turned and the hull or boat caused to move forward or rearward if a reverse movement is imparted to the shaft 6.

5 That the whole work of propelling the boat may not be imposed upon one operator, provision is made for a second operator adjacent the prow. To this end there is mounted in the prow end of the hull the two pillar blocks 18, formed with appropriate bearings for the support of a transverse shaft 19, provided with cranks 20 for the imparting of rotary movement, just as is done in the case of the shaft 6. An operator's 10 seat 21 is positioned convenient to the cranks 20 and this seat is carried on a column 22, the seat 21 and its column 22 being identical with the seat 4 and column 3.

15 The shaft 19 is operatively connected with the propeller shaft 16, and to provide for this a column 23 is positioned between the pillar blocks 18 and below the shaft 19. In the upper end of this column there is journaled a shaft 24 which carries a bevel gear 25 and a pinion 26, the pinion meshing with a spur gear 27, carried by the shaft 19 so that 20 rotary movement imparted to the shaft may be communicated to the shaft 24.

25 A longitudinal shaft 28 is journaled in an appropriate bearing in the column 22 and in a similar bearing in the column 8 and at the forward end carries a bevel gear 29, meshing with the bevel gear 25, this same shaft carrying at the rear end a bevel gear 30, meshing with the bevel gear 15 carried 30 by the propeller shaft 16. It is obvious from the construction just described that the rotation of the shaft 19 through the instrumentality of its cranks 20 may serve to 35 impart rotary motion to the propeller shaft 40 and to the propeller, in either direction, depending on the direction in which the shaft 19 is turned. Thus it is apparent that either the shafts 16 or 19 may be rotated for driving 45 the propeller 17, or, that the two may be used together for the turning of the propeller, the latter plan obviously providing for increased force in the turning of the propeller with the result that the latter may 50 be revolved more quickly than when either shaft 16 or 19 is turned alone.

55 A rudder 31 is mounted for swinging movement at the stern of the hull, being carried by the latter according to well known methods of construction. This rudder at the upper end carries a transversely disposed bar 32 projecting laterally from opposite sides of the rudder and having connected with its opposite ends the terminals 60 of flexible members 33, the remaining terminals of these two members being led respectively to depressible foot pedals 34, carried on opposite sides and to the forward 65 of the seat 4 so that the occupant of the latter may be in position to depress either

pedal with one foot for the obvious rocking of the rudder 31 in one direction or the other.

60 The peculiar construction herein shown makes for the ready propulsion of the boat without excessive friction. No packing box 70 is required for the propeller shaft because the latter enters the hull through the forward or upper end of the tube 2 which is above the water line. Therefore, no water may enter the hull and since no packing box 75 is required, the propeller shaft may be turned freely and the only resistance encountered in the operation of such shaft is that due to the loss of power in the bearings of the several shafts and in the geared 80 connections between them. Since the efficiency of gear transmission is very high, it is apparent that a relatively small amount of power is lost between the shafts 19 and 6 85 and the propeller 17.

90 It will be observed that the two cranks 20 carried on the shaft 19 project in the same radial direction. There is therefore no angular displacement between these cranks and the turning of the shaft results in a movement of the body similar to that obtaining when rowing. The cranks 7 are similarly disposed on their shaft 6 but these cranks are angularly disposed with reference to the cranks 20. Assuming that a 95 turning force is imparted to the shaft when the cranks are being pulled backward, the cranks 20 are active in exerting this force when the cranks 7 are passive and vice versa. Thus when two operators are occupying the boat, the two by operating their respective shafts may impart a substantially continuous rotating force to the propeller shaft with the result that the boat will run smoothly. 100

105 The invention having been described, what is claimed as new and useful is:

1. The combination with a boat, of a tubular member disposed within the boat and having one end penetrating the stern of the latter adjacent the bottom thereof, said tubular member inclining upwardly in a forward direction and terminating above the water line at which the boat sets when fully loaded, a shaft journaled in the tubular member and protruding from both ends thereof, a propeller carried by the rear protruding end of the shaft, a pair of rotatably mounted transversely disposed shafts carried in the boat, the one being positioned adjacent the forward end of the first said shaft and the other adjacent the prow of the boat, a crank carried on each end of each transverse shaft, the two cranks on the same shaft having the same radial direction, and operative connections between the two transverse shafts and the first said shaft, the cranks on the two transverse shafts being angularly displaced in the manner and for the useful purpose specified. 110 115 120 125 130

2. The combination with a boat, of a tubular member disposed within the boat and having one end penetrating the stern of the latter adjacent the bottom thereof, said tubular member inclining upwardly in a forward direction and terminating above the water line at which the boat sets when fully loaded, a shaft journaled in the tubular member and protruding from both ends thereof, a propeller carried by the rear protruding end of the shaft, a pair of rotatably mounted transversely disposed shafts carried in the boat, the one being positioned adjacent the forward end of the first said shaft and the other adjacent the prow of the boat, a crank carried on each end of each transverse shaft, the two cranks on the same shaft

having the same radial direction, a rotatably mounted longitudinal shaft disposed within the body, a rotatably mounted shaft disposed below the forward transverse shaft, a gear couple connecting the forward transverse shaft with the last said shaft, a gear couple connecting the last said shaft with the longitudinal shaft, a gear couple connecting the longitudinal shaft with the first said shaft, and a gear couple connecting the remaining transverse shaft with the first said shaft, the cranks on the two transverse shafts being angularly displaced in the manner and for the useful purpose specified.

In testimony whereof I affix my signature.

YUST PETERSON.
